UNITED STATES PATENT OFFICE

105,171

DESIGN FOR A GAS BURNER

Nis M. Hansen, San Francisco, Calif.

Application October 12, 1936, Serial No. 65,271

Term of patent 14 years

To all whom it may concern:

Be it known that I, Nis M. Hansen, a citizen of the United States of America, residing at San Francisco, in the county of San Francisco and State of California, have invented a new, original, and ornamental Design for a Gas Burner, of which the following is a specification, reference being had to the accompanying drawing, forming a part thereof.

The figure is a perspective view of a gas burner, showing my new design, the side not shown being the same.

I claim:—

The ornamental design for a gas burner substantially as shown and described.

NIS M. HANSEN.
